WASHING MACHINE PROVIDED WITH
ADJUSTABLE FLOAT VALVEFrancis H. Condon, Detroit, Mich., assignor to
Borg-Warner Corporation, Chicago, Ill., a cor-
poration of Illinois

Application September 18, 1947, Serial No. 774,832

8 Claims. (Cl. 68—12)

1

This invention has to do with a liquid level control for automatic washing machines and the like. More specifically, the invention is directed to the regulation of the amount of liquid to be used at any time in an automatic or semi-automatic cycle washer, and to preselective means securing said regulation in conjunction with the automatic controls for the washer.

It is an object of the present invention to provide a means for preselecting the amount of liquid to be valved to the washing machine. In this connection it is an object to provide a means which is especially adaptable for use with a so-called automatic cycle washing machine wherein all or a part of the washing operation may be performed by automatic sequential controls.

Heretofore, in the performance of washing actions, even when there has been automatic sequential control, the only method of varying the liquid level has been a haphazard manual operation in which the mechanism controlling the inflow of water is moved manually to an advanced position so that less liquid is admitted to the tub. Such a method of operation has to be repeated each time the tub is charged, that is, for the soaking action, for the washing action, and for the various rinses. As a result, the automatic features of the machine are lost. Further, it is more or less guess work as to how much liquid will be admitted to the tub under such manual operation.

Also, in the past, with washing machines of the automatic type, it has been the practice to determine a preferential water level, so that the machine in its soaking, washing and rinsing operations automatically valves the water to secure the same water level.

Many homes have a limited supply of water, and this is particularly true in the case of hot water. As a result, previous automatic washers have not met with full favor and especially the larger washers using a considerable amount of water.

It is an object of the present invention to provide an arrangement whereby the amount of liquid for automatic cycle or semi-automatic cycle washing machines may be preselected prior to operation of the machine.

In many instances, it is desirable to be able to preselect a definite water level. For example, certain types of garments do not require as much water as other types. Where the user has any reason to conserve hot water, for example, or in the interest of economy, or where the amount of clothes is less than the intended capacity of the

2

machine, frequently, it would be an advantage to be able to preselect a smaller amount of water than that which would be used under other conditions. It is an object of the present invention to provide a device for accomplishing this purpose.

It is a further object of the present invention to provide an arrangement in which the user may vary the amount of water to be admitted for any washing operation, and may preselect the amount desired by a change in setting after the device is in operation. For example, perhaps in the soaking stage, a considerable amount of water is desired and it is an object of this invention to enable the operator to obtain the amount by setting an indicator for the maximum amount of water. In certain types of washes, the soaking may remove the larger portion of the soil from the items being washed, and in such event the user may desire less water for the actual wash cycle wherein the most hot water is used and wherein the clothes are usually sudsed and particularly since the clothes are already in the damp or wet stage. In such event, after the tub has been filled, for the soak stage, the operator by moving the indicator to a definite position, for example, the medium position or the low position, can preselect the amount of water admitted for the later wash operations at that position.

It is an object, broadly, of this invention to define means determining the quantity of water to be admitted to the tub. In this connection, there is disclosed a means determining the amount of water on a basis of the water level in the tub.

Specifically, it is an object of the present invention to provide an arrangement wherein a washing machine tub is provided with a float tank in communication therewith, said float tank being adapted to reflect the water level in the tub and switch means actuated by a float in the float tank adapted to energize and deenergize, as the case may be, means setting the liquid admitting valve for opening and closing by the automatic sequential controls for the machine. The switch means is arranged for a variable setting, which variable setting may be predetermined by an indicator on the machine.

Further, it is an object to provide an arrangement which is relatively inexpensive and which may be manufactured under modern conditions and with modern production machinery, the structure being rugged and practically foolproof.

It is an object of the present invention to provide an arrangement which overcomes objectionable features heretofore present in automatic washers, and particularly an object to overcome the objectionable features above referred to.

Other objects, advantages and uses of the invention will be apparent from a further description of the invention herein, and from the drawings, wherein:

Fig. 1 is a front elevational view of a preferred form of washing machine embodying the present invention; 10

Fig. 2 is a rear elevational view disclosing the present invention, and showing the arrangement of the mixing valve, source of fluid or liquid for the machine, and the device of the present invention attached to the machine. Fig. 2 is without the cabinet illustrated in Fig. 1; 15

Fig. 3 is a fragmentary, enlarged elevational view showing details of construction of a device embodying the present invention; 20

Fig. 4 is a fragmentary, enlarged view partially in section, taken on the line 4—4 of Fig. 3 looking in the direction of the arrows; 25

Fig. 5 is a top plan view taken on the line 5—5 of Fig. 3 looking in the direction of the arrows; and 30

Fig. 6 is a top plan view taken on the line 6—6 of Fig. 3 looking in the direction of the arrows.

Referring further in detail to the construction shown in the drawings, and referring first to the arrangement of Fig. 1, there is illustrated a washing machine of the type generally referred to as the horizontal axis automatic cycle washer. Fig. 1 discloses the cabinet or wrapper 20, in which is located a washing machine tub. The cabinet 20 has the control knob 22, which is used in setting the control mechanism of the machine for its various operations, herein referred to as automatic sequence controls. The details of the mechanism operated by said control knob are not necessary to be disclosed here, as they are well known in the art.

A water temperature switch control 24 enables the operator of the machine to preselect the temperature of the water for the washing operations. Here again it is not necessary to describe this mechanism as it also is well known. A dial plate 26 is provided, the dial plate normally having markings thereon (not shown) indicating the settings of the control knob 22 and the switch control 24. There is provided on said washing machine means indicating the water level, which means here is shown as the water level selector switch 28, and the dial plate 30. The dial plate 30 as shown in Fig. 1 preferably has means indicating the amount of liquid to be admitted, the means here being shown as the letters "L," "M" and "H." Respectively, the letters are intended to represent "Low," "Medium" and "High" settings. The washing machine is preferably provided with an access door 32 for charging and removing clothes or items to be washed (herein usually referred to as clothes) from the machine.

Referring next to Figs. 2 and 3, there is shown a tub 232 of a washing machine, which tub 232 ordinarily would be mounted in a cabinet 29, of the type shown in Fig. 1. As here disclosed, the tub 232 is of the type used in a horizontal axis washer, and is mounted on a base 233. Attached to the base 233 adjacent the back of the tub 232 is a vertically elongated float tank 234, said float tank being attached by any 70

convenient means, such, for example, as the bracket 236.

The tank 234 has a liquid connection to the bottom of the tub 232. In this illustration a generally horizontally disposed tube 238 extends from the bottom of the tank 234 to the bottom of the tub 232. By this means, the liquid level in the tub will be the same as the liquid level in the tank.

The float tank 234 contains the float 240, which float 240 rises and descends with respect to the tank in accordance with the liquid level in the float tank 234. The float 240 carries the upwardly extending rod 242, which extends upward through a suitable aperture 243 in a switch stop 244 shown in Fig. 5. The switch stop 244 is vertically adjustable being carried by a downwardly depending hollow arm 239 as shown in Figs. 3 and 5 in the lower portion of which the upper end of push rod 242 is received. The arm 239 is pivotally supported at its upper end on the right end of crank arm 254, the left end of which is fixed to the rear end of a control shaft 256 as shown in Fig. 4. Otherwise stated, the upwardly extending rod 242 cooperates with the hollow arm 239 in telescoping relationship. The shaft 256 has affixed to its opposite end (not shown) the water level indicator or selector knob or handle 28. The shaft 256 is rotatably journaled to the bracket 268. It will thus be obvious that rotation of the shaft 256 by rotation of the knob or handle 28 will move the outer end of the arm 254 up and down, thereby raising and lowering the switch stop 244. The bracket 268 may be L-shaped and have an outwardly extending arm 278, the outer end of which is suitably apertured to form a guide for maintaining the vertical alignment of downwardly depending arm 239.

The float tank is provided at its upper edge with a fixed lower switch stop 246 in the manner shown, particularly in Figs. 2 and 3.

The upwardly extending rod 242 carried by the float 240, has mounted thereon a toggle switch 250 with an actuating arm 248 and electrical connections 272 and 273, forming a part of the circuit for controlling solenoid actuated valve 215. It will thus be seen that movement of the rod 242 upward will cause the arm 248 of the switch 250 to engage the stop 244 when the arm reaches the upper limit. This will pivot the arm 248 downwardly and trip the switch, de-energizing solenoids hereinafter described, and cutting off the flow of water. Conversely, when the switch and rod 244 move downward as the water is drawn from the tub, the arm 248 contacts the lower switch stop 246 and throws the switch, thus enabling the circuit to be energized by the sequential controls whereby the water or other fluid is allowed to flow into the tub 232, in the manner hereinafter described.

Referring specifically to Fig. 2, there is shown a source of hot water 211 and a source for cold water 213, here shown as conduits or pipes, to the mixing valve 215. The mixing valve 215 is provided with solenoids 217 in the construction shown, which solenoids are actuated by the sequence switch 22 and under control of the water temperature switch 24. It will be noted that the toggle switch 250 is in one line of the circuit as represented by the numbers 273 and 272, so that when the switch is in the "on" position, the solenoids may be energized to open the valve and when in the "off" position the water inlets remain closed.

For the purpose of enabling the operator to select the proper water level, there is provided a plate 262 (see Figs. 3 and 4), which is mounted upon and rotates with the shaft 256, the plate 262 being located adjacent the right side of bracket 268, as viewed in Fig. 4. A spring actuated detent 264 is carried by the bracket 268 and the plate 262 has three depressions 266 to receive the detent at its various positions. The arrangement shown here provides for three different water levels, although obviously others could be supplied. It is desirable that the arrangement is such as to prevent movement of the water level control switch past its limits in either direction and for this purpose I have provided the stops 258 and 260 as shown in Fig. 3, which are adapted to engage the side edges of plate 262 to limit the rotation of shaft 256.

A small water conduit 274 is provided, as shown in Fig. 2, which extends at its delivery end from the water inlet, here shown as the mixing valve 215, to a position above the tank 234 and the delivery end is spaced therefrom a sufficient distance so that if suds form in the tank 234, there is little or no danger of them being drawn into the water system for the house. This feature is important in that the various health regulations require a vacuum breaker or other means to prevent backflow which might contaminate the water system.

A further feature of this invention is that the size of the pipe 274 is selected so that a proportionate amount of water to that flowing into the tub proper, flows direct from the inlet to the tank. In this way, the tank will be filled at approximately the same speed as the tub and there is little or no tendency of soiled water from the tub to flow into the tank. It is essential, however, that the water not flow into the tank substantially faster than it flows into the tub, inasmuch as the float might be raised and cut off the flow of water to the tub and tank before the full amount desired has been obtained.

In the operation, the device works substantially as follows:

Assuming that the tub is empty and the float 240 is at its bottom position, the switch 250 is in the "on" position. When the sequence of operations is started by the movement of the control switch 22, water will enter through the conduits 211 and 213 into the mixing valve 215, and be discharged to the tub 232 through the nozzle 218. At the same time, water will flow into the tank 234 from the pipe 274, (usually raising the level in tank 234 slightly faster than in tub 232). If there is any variation in rate of filling, it will be equalized through the tube 238, when the solenoids shut off the water. The water levels will balance and water will flow from tank 234 to tub 232 thereby keeping suds, etc., out of the tank 234. As the float rises, the toggle switch 250 is carried upward until its arm 248 contacts the stop 244. This stop, as shown in Fig. 3, is in its medium position. It can be lowered by turning the water selector knob 28 to its L position. Once set, however, after the arm 248 has thrown the switch, the water level in the tub cannot normally be varied until after the water has been drained out of the tub.

However, the position of the stop 244 may be changed between operations, or may be left in a selected position for all of the operations. It will thus be seen that by this means there is provided an arrangement whereby the operator

can preselect the amount of water for any operation or series of operations caused by the sequential control for the machine. In actual practice, the user will determine how much water is desired, will set the water selector accordingly, and thus not need to give any further consideration to the amount of water in the machine as it will be controlled automatically.

While I have described my invention in connection with one specific embodiment thereof, it is to be understood that this is by way of illustration and not by way of limitation and the scope of my invention is defined solely by the appended claims which should be construed as broadly as the prior art will permit.

What is claimed is:

1. A fluid level selector control for a liquid receptacle such as a washing machine comprising a tank adjacent said receptacle, a float in said tank, means for establishing a liquid level in said tank substantially representative of the liquid level in said receptacle, and a solenoid operated valve for controlling admission of fluid to said receptacle, comprising means for establishing the liquid level in said receptacle and including a switch, means supporting said switch on said float so that said switch rises or descends in accordance with the fluid level in said tank, a first switch actuating means engageable by said switch in an upper position of said float to open said switch, a second switch actuating means engageable by said switch in a lower position of said float to close said switch, and means controllable from a point remote from said switch actuating means and including means for slidably receiving said switch supporting means and for adjusting the position of said first switch actuating means.

2. A fluid level selector control for a liquid receptacle such as a washing machine comprising a tank located adjacent said receptacle, means for establishing a fluid level in said tank substantially representative of the fluid level in said receptacle, a float disposed in said tank and adapted to move vertically correspondingly to the liquid level in said tank, a rod mounted on said float and movable therewith, a switch supported on said rod and movable therewith, an operating lever for said switch and carried by said switch and extending generally at right angles to the path of movement of said switch, a first, fixed operating lug engageable by said lever in a lower position of said float for shifting said switch lever to a first position, and a second adjustably mounted operating lug engageable by said lever in an upper position of said float to shift said switch lever to a second position and means including means for receiving said rod and means disposed remote from said receptacle for positioning said rod receiving means thus adjustably positioning said adjustable mounted operating lug.

3. A fluid level selector control for a liquid receptacle such as a washing machine comprising a tank located adjacent said receptacle, means for establishing a fluid level in said tank substantially representative of the fluid level in said receptacle, a float disposed in said tank and adapted to move vertically correspondingly to the liquid level in said tank, a rod mounted on said float and movable therewith, a switch supported on said rod and movable therewith, an operating lever for said switch and carried by said switch and extending generally at right

angles to the path of movement of said switch, a first, fixed operating lug engageable by said lever in a lower position of said float for shifting said switch lever to a first position, a second adjustably mounted operating lug engageable by said lever in an upper position of said float to shift said switch lever to a second position, means for supporting said second operating lug comprising a tube in the lower end of which the supporting rod for said switch is receivable, a pivotally mounted bracket supporting said tube, and means for pivoting said bracket to raise or lower said tube and the lug supported thereby with respect to the fixed lug.

4. A fluid level selector control for a liquid receptacle such as a washing machine comprising a tank located adjacent said receptacle, means for establishing a fluid level in said tank substantially representative of the fluid level in said receptacle, a float disposed in said tank and adapted to move vertically correspondingly to the liquid level in said tank, a rod mounted on said float and movable therewith, a switch supported on said rod and movable therewith, an operating lever for said switch and carried by said switch and extending generally at right angles to the path of movement of said switch, a first, fixed operating lug engageable by said lever in a lower position of said float for shifting said switch to a first position, a second adjustably mounted operating lug engageable by said lever in an upper position of said float to shift said switch to a second position, means for supporting said second lug comprising a vertically adjustable tube in the lower end of which the axially movable rod is receivable and to the lower end of which the second lug is affixed, and crank arm defining means affixed to said tube for moving said tube with respect to said fixed lug.

5. In a washing machine of the class described having automatically operable sequential controls and liquid charging means for charging a tub in the machine with liquid and for performing at least part of the washing action, a float tank mounted adjacent the tub, a float in said tank, and conduit means establishing a liquid level in the tank substantially the same as that of the liquid level in the tub so that the position of the float is representative of the liquid level in the tub, the improvements in variable pre-selecting means for controlling the amount of liquid admitted to the tub which comprises a rod mounted on said float and responsive thereto, electrical switch means on said rod in circuit with the liquid charging means for said machine, means including means engageable by said electrical switch means so that said switch means can effect control of the liquid charging means in response to movement of said rod, and means including rod receiving means controllable from a point remote from said float tank for varying the position of one of said means which are engageable by said electrical switch means.

6. A fluid level selector control for a liquid receptacle comprising a tank located adjacent said receptacle, means for establishing a fluid level in said tank substantially representative of the fluid level in said receptacle, a float disposed

in said tank and adapted to move vertically corresponding to the fluid level in said tank, and means including telescoping means comprising an element attached to said float and movable in response thereto, and a second element for receiving said first element in telescoping relation, the position of the latter element with respect to said first element and said tank being variable, any position of which will be determinative of the fluid level in said receptacle as represented by the fluid level in said tank.

7. A fluid level selector control for a liquid receptacle comprising a tank located adjacent said receptacle, means for establishing a fluid level substantially representative of the fluid level in said receptacle, a float disposed in said tank and adapted to move vertically corresponding to the fluid level in said tank, means including telescoping means comprising an element attached to said float and movable in response thereto, and a second element for receiving said first element in telescoping relation, the position of the latter element with respect to said first element and said tank being variable, any position of which will be determinative of the fluid level in said receptacle as represented by the fluid level in said tank, and mechanical means for varying the position of the second element.

8. A fluid level selector control for a liquid receptacle comprising a tank located adjacent said receptacle, means for establishing a fluid level in said tank substantially representative of the fluid level in said receptacle, a float disposed in said tank and adapted to move vertically corresponding to the fluid level in said tank, means including telescoping means comprising one element attached to said float and movable therewith and a second element for receiving said first element in telescoping relationship, switch means on said first element, switch actuating means on said tank and said second element, the position of the second element and said switch actuating means being determinative of the fluid level in said receptacle as represented by the fluid level in said tank and means for positioning said second element and said switch actuating means thereon with respect to said first element.
